UNITED STATES PATENT OFFICE.

EDWARD CURTIS BATES, OF GRAND FORKS, NORTH DAKOTA.

DEVICE FOR HOLDING COLLARS, NECKTIES, &c.

No. 833,366.

Specification of Letters Patent.

Patented Oct. 16, 1906.

Application filed June 8, 1905. Serial No. 264,816.

To all whom it may concern:

Be it known that I, EDWARD CURTIS BATES, a citizen of the United States, residing at Grand Forks, in the county of Grand Forks, 5 and State of North Dakota, have invented a new and useful Device for Holding Collars, Neckties, &c., of which the following is a specification.

The invention relates to a device for holding collars, neckties, &c.

The object of the present invention is to provide a simple, inexpensive, and efficient device designed particularly for use in a barber-shop for holding collars, neckties, &c., 5 and adapted to be readily applied to the arm of a barber's chair, a shelf, or other convenient place, and capable of securely holding a collar, necktie, or other small article without soiling or mussing the same.

A further object of the invention is to provide a device of this character adapted to be readily operated for enabling a collar, necktie, &c., to be placed on it and capable when released by the operator of automatically 25 clamping the articles held by it.

With these and other objects in view the invention consists in the construction and novel combination and arrangement of parts hereinafter fully described, illustrated in the 30 accompanying drawings, and pointed out in the claims hereto appended.

In the drawings, Figure 1 is a side elevation of a device constructed in accordance with this invention and shown applied to the 35 arm of a barber's chair. Fig. 2 is a vertical sectional view taken substantially on the line 2 2 of Fig. 1. Fig. 3 is a detail vertical sectional view taken at right angles to Fig. 2 and showing the means for retaining the 40 inner tube or sleeve within the outer tube or casing. Fig. 4 is a detail perspective view of the combined supporting and clamping plate and the inner tube or sleeve. Fig. 5 is a detail perspective view of the outer tube or 45 casing.

Like numerals of reference designate corresponding parts in all the figures of the drawings.

1 designates an outer tube or casing constructed of suitable metal and provided at the 50 top with an attachment-flange 2, which may be of segmental or any other shape and which is perforated for the reception of screws or other suitable fastening devices for securing 55 it to the arm 3 of a barber's chair or to a shelf or other suitable support. The outer

tube or casing, which is closed at the bottom, houses a coiled spring 4, and it forms a guide for an inner tube or sleeve 5, which is closed at the top 6 and which is engaged by the 60 upper end of the coiled spring for holding a combined clamping and supporting plate 7 against the lower face of the arm 3 and for causing the said plate to clamp and securely hold the collar, necktie, or other article 65 placed on the plate. The plate 7, which is horizontal and preferably rectangular, is connected with the upper end of the inner tube by a narrow neck or connecting portion 8, and the adjacent side of the outer tube or 70 casing is provided with a vertical slot 9, through which the neck passes and in which the neck slides when the plate is raised or lowered. The plate is provided at its outer edge with an upwardly-extending flange or 75 wall 10 for preventing the collar or necktie from slipping off its outer end, and the flange or wall is arranged to fit against the outer edge of the arm 3 when the plate is in engagement with the lower face of the arm as 80 clearly illustrated in Fig. 2 of the drawings.

The device is provided with a grip or handle 11, having a shank 12 extending downward from the lower face of the plate 7, near the inner end thereof, and preferably 85 enlarged at the top and secured to the upper end of the inner sleeve or tube. The grip or handle is adapted to be readily engaged by the thumb for moving the plate downward to permit the collar and necktie to be placed 90 on the same, and as soon as the grip or handle is released the plate will be automatically moved upward by the coiled spring, and the collar and necktie or other article will be clamped between the plate and the lower 95 face of the arm 3, whereby such article will be securely held and positively prevented from accidentally falling from the device. The device may be applied to either of the 100 arms of a barber's chair or at any other suitable place in a barber-shop, and it may also be employed in other places for kindred purposes.

When the device is not applied to a chair or other support, the inner tube or sleeve is 105 retained within the outer tube or casing by means of a screw 13, piercing the outer tube or casing near the upper end thereof and engaging suitable screw-threads thereof and extending into the same. The inner projecting end of the screw is arranged to engage 110 the inner tube or sleeve, which is provided

at the top with a recess 14, as clearly illustrated in Fig. 3 of the drawings. The recess 14 extends downwardly from the upper end of the inner tube or sleeve, so that the screw 5 will not interfere with the vertical movement of the same.

Having thus fully described my invention, what I claim as new, and desire to secure by Letters Patent, is—

- 10 1. A device for holding collars, neckties, &c., comprising a guide provided with means for securing it to the lower face of the arm of a chair, shelf, &c., a support slidable on the guide and arranged to receive a collar, necktie, &c., and means for yieldably holding the support against the lower face of the said arm or shelf to clamp the articles carried by the support.
- 15 2. A device for holding collars, neckties, &c., comprising a combined supporting and clamping plate arranged in a horizontal position to form a support for a collar, necktie, &c., and means for yieldably holding the plate against the lower face of the arm of a chair, shelf, &c., to clamp the articles supported by the plate, the latter being movable from the lower face of such arm or shelf to release the said articles.
- 20 3. A device for holding collars, neckties, &c., comprising a vertical guide provided at its top with means for securing it to the lower face of the arm of a chair, shelf, &c., a plate slidable on the guide to and from the said lower face and arranged horizontally to form a support for a collar, necktie, &c., and means for yieldably holding the plate against said arm or shelf for clamping the articles supported by the said plate.
- 25 4. A device for holding collars, neckties, &c., comprising a vertical guide provided with means for securing it to the lower face of the arm of a chair, shelf, &c., a plate slid- able on the guide to carry it to and from such arm or shelf and arranged horizontally to form a support for a collar, necktie, &c., said plate being also provided at its front with a vertical flange or wall arranged to fit against the edge of the arm or shelf, and means for yieldably holding the plate against said arm or shelf for clamping the collar or necktie.
- 30 5. A device for holding collars, neckties, &c., comprising a vertical guide provided at the top with means for securing it to the lower face of the arm of a chair, shelf, &c., a plate provided at the back with means slid- able in the guide for moving the plate vertically toward and from the arm or shelf, said plate being arranged horizontally to form a support for a collar, necktie, &c., and a spring housed within the guide and engaging the said means for yieldably holding the plate against the arm or shelf to clamp the articles supported by the plate.
- 35 6. A device for holding neckties, &c., comprising a tubular guide arranged vertically and provided at the top with an attachment-flange, a plate arranged horizontally to form a support for a collar, necktie, &c., and provided with a tube slidable in the guide, a spring housed within the guide and engaging the slidable tube for moving the plate upwardly to cause the same to clamp the articles supported by it, and a handle located beneath the plate and connected with the same for moving the said plate downwardly to release the articles.
- 40 7. A device for holding collars, neckties, &c., comprising a vertical guide provided with means for securing it to the lower face of the arm of a chair, shelf, &c., a plate slidably connected with the guide and arranged horizontally to form a support for a collar, necktie, &c., means for yieldably holding the plate against such arm or shelf to clamp the articles supported by the said plate, and a handle located beneath the plate for moving the same downwardly.
- 45 8. A device for holding collars, neckties, &c., comprising a vertical tubular guide having a longitudinal slot at the front and provided at the top with means for securing it to the lower face of the arm of a chair, shelf, &c., an inner tube slidable in the guide, a plate arranged horizontally to form a support for a collar, necktie, &c., and provided with means extending through the slot of the guide for connecting the said plate with the inner tube, a coiled spring housed within the guide and extending into the inner tube and engaging the same for yieldably holding the plate against the arm or shelf to clamp the articles supported by the said plate, and a handle located beneath the plate and connected with the same.
- 50 9. A device for holding collars, neckties, &c., comprising a vertical tubular guide having a slot at the front and provided at the top with means for securing it to the lower face of the arm of a chair, shelf, &c., an inner tube slidable in the guide, a horizontal plate having means located at its rear edge and operating in the slot for connecting it with the inner tube, a spring housed within the slot and engaging the inner tube for yieldably holding the plate against the said arm or shelf, said plate being also provided at its front with a vertical wall or flange, and a handle having means operating in the slot for connecting it with the plate.
- 55 10. In testimony that I claim the foregoing as my own I have hereto affixed my signature in the presence of two witnesses.

EDWARD CURTIS BATES.
